UNITED STATES PATENT OFFICE.

JAMES ALEXANDER BURKE, OF LIGONIER, PENNSYLVANIA.

WINDOW-FASTENER.

1,225,763.

Specification of Letters Patent. Patented May 15, 1917.

Application filed March 31, 1916. Serial No. 88,109.

To all whom it may concern:

Be it known that I, JAMES A. BURKE, a citizen of the United States, residing at Ligonier, in the county of Westmoreland and State of Pennsylvania, have invented 5 certain new and useful Improvements in Window-Fasteners, of which the following is a specification.

This invention relates to an improved 10 window fastener and the principal object of the invention is to provide a fastener so constructed that a window may be releasably held at a desired position in the frame and to further construct the fastener that 15 it will be normally held in a position for engagement with a rack connected with the window frame, the engaging plunger being yieldably held in the operative position and provided with means for permitting of its 20 being easily moved to an inoperative position.

Another object of the invention is to so construct this fastener that the racks forming part of the same may take the place of 25 the usual guiding strip for the window frame.

Another object of the invention is to provide a fastener which will be very simple in construction and which can therefore be 30 produced at a very small cost.

This improved window lock is illustrated in the accompanying drawings, wherein:—

Figure 1 is a view in front elevation showing the device applied to a window.

Fig. 2 is a sectional view taken along the line 2—2 of Fig. 1.

Fig. 3 is a view in elevation of the fastener with the front plate removed.

This improved fastener is used for 40 releasably holding the upper and lower window sashes 10 and 11 at a desired position in the window frame 12 and may be positioned either at the side shown in Fig. 1 or upon the opposite side. It is also obvious 45 that if desired, a fastener can be provided at each side of the window. When in use the beading is removed from that side of the window frame 12 with which the fastener is to be connected and the racks 13 50 are put in place where they will serve as means for guiding the movement of the window sash in the frame. These racks are each provided with a flange or extension 14 through which the securing screws or other 55 fasteners 15 indicated by dotted lines in Figs. 1 and 2 will pass. These racks are

provided with teeth 16 for engagement by the fasteners carried by the window sashes and it will thus be seen that when the window sashes are moved vertically in the window frame they may be releasably held at the desired position.

The fastener is provided with a housing 17 having an inturn flange 18 forming a good support for the cover plate 19, the 65 cover plate being held in engagement with the housing by means of screws or other fasteners 20 which pass through openings 21 formed in the flange 18. The latch pin 22 which engages the teeth of the rack bars 70 is slidably mounted in the housing and is yieldably held in the extended or operative position by means of the spring 23 positioned as shown in Fig. 3 and engaging the head 24 of the latch pin. A stem or actuating handle 25 extends from the latch pin 22 through the top portion of the housing 17 and may be bent as shown in Fig. 3 to permit easy handling of the same or may be provided for connection with a line or 80 chain 26 as shown at the upper portion of Fig. 1.

When this device is in use the handle 25 of the lower fastener will be moved with one finger and as soon as latch pin 22 is out 85 of engagement with the racks 13, the lower sash can be raised and the latch pin then released and permitted to return to the operative position. In order to lower the upper sash, the line or chain is drawn to 90 move the latch pin to the inoperative position and the upper sash can then be lowered to the desired point. The line or chain can then be released and the upper sash will be releasably held at the adjusted position. It 95 will thus be seen that this device is very simple in construction but at the same time is very effective in use and will not easily get out of order or need repairs.

What is claimed is:—

A window frame, a sash slidably mounted in said frame, a strip guiding the movement of said sash and provided with a toothed flange forming a rack bar, a housing connected with said sash and having its walls 105 provided with inwardly extending flanges, a closure plate fitting against the flanges of said housing and connected therewith, a latch pin slidably mounted in said housing and extending through one end thereof, an 110 abutment head at the inner end of said latch pin curved transversely, a spring positioned

110

between said head and one of the end walls of said housing to yieldably hold said latch pin in an extended position for engagement with said rack bar, and an actuating pin extending from said latch pin and having its outer end portion bent to provide an engaging hook.

In testimony whereof I affix my signature in presence of two witnesses.

JAMES ALEXANDER BURKE.
